UNITED STATES PATENT OFFICE

HUGH M. STEPHENSON, OF FORT WAYNE, INDIANA, ASSIGNOR TO GENERAL ELECTRIC COMPANY, A CORPORATION OF NEW YORK

SEWING-MACHINE FEEDING MECHANISM

Application filed June 9, 1927. Serial No. 197,584.

My invention relates to sewing machines, and more particularly to feeding mechanisms therefor.

An object of my invention is to provide an improved feeding mechanism including an oscillatory shaft for transmitting motion from a feed actuating and adjusting means to the feed-dog of the feeding mechanism in which the adjusting means is compactly arranged so that it can be readily enclosed in order to avoid noisy operation of the machine and, if desired, to retain oil for lubrication of the moving parts therein.

A further object of my invention is to provide a feeding mechanism which is adjustable for reversing the direction of feed of the mechanism and for varying the length of the stitch formed by the machine in sewing forward or backward.

20 My invention will be more fully set forth in the following description referring to the accompanying drawings, in which Fig. 1 is a side elevation of a sewing machine embodying my invention partly broken away to more

25 clearly illustrate the construction; Fig. 2 is a plan view of the underneath portion of the bed-plate of the structure shown in Fig. 1, broken away in part; Fig. 3 is an end elevation of the structure shown in Fig. 1 looking toward the end of the arm of the machine;

Fig. 4 is a sectional view approximately on the line 4—4 of Fig. 1; Fig. 5 is a perspective view of the feeding mechanism, showing the feed-dog bar in its relation to the presser-

30 foot and the bed-plate of the sewing machine; Fig. 6 is an enlarged transverse section of the feed adjusting and actuating means shown in Fig. 4; Fig. 7 is a sectional view of the arm used for transmitting motion from the oscillating shaft to the feed-dog bar showing the latter in its lowermost position; and

35 Fig. 8 is a view of the parts shown in Fig. 7 in a position in which the feed-dog bar is in its uppermost position.

40 Referring to the drawing, the sewing machine illustrated includes a bed-plate 10 from which extends an overhanging arm 11 for supporting the needle bar 12, presser-foot 13, take-up 14 and its actuating cam 15. The 45 form of take-up illustrated is not part of

the present invention, but is of the same general construction as that described and claimed in my application, Serial No. 205,480 filed July 13, 1927. As illustrated in Fig. 3 the bobbin cage 16 is retained within the 55 rotary loop taker 17 below the bed-plate 10, and these parts cooperating with the needle bar, presser-foot and the feeding mechanism form the usual lock stitches in ordinary operation of the machine. The machine is 60 driven by an electric motor 50 which is secured underneath the bed-plate 10 for driving an actuating shaft 55. The motor is connected through a coupling 51 to a pinion 52 which drives a gear 53 supported on a vertical shaft 54 extending above the top of the machine to serve as a bobbin winder described and claimed in my application Serial No. 200,726 filed June 22, 1927. A loop-taker 65 actuating shaft 55 is driven by the shaft 54 70 by means of gears 56 and 57 secured to the shafts 54 and 55 respectively. The needle bar and take-up mechanisms are driven by the horizontal and vertical shafts 59 and 28, the latter being connected to the shaft 55 by 75 means of gears 55^a and 58. The lower end of the shaft 28 rotates a cam 27 which operates my improved reversible feeding mechanism which will be hereinafter more fully described.

80 The reversible feeding mechanism includes the usual form of four-motion feed-dog 18 which is supported underneath the bed-plate 10, and which is reciprocated over a range of movement corresponding to the length of the 85 stitch formed by the machine. In feeding material through the machine when sewing forwardly the feed-dog is first raised against the material at the end of its stroke adjacent the tip of the presser-foot 13 slightly raising the latter, moves in the direction of feed toward the presser bar 13^a to the end of its stroke after which it is lowered out of engagement with the material being sewn, retracted in its lowered position to the other end of the 90 stroke, and is again raised against the material under the presser-foot 13.

95 The foregoing described movement of the feed-dog is the same as that generally employed in machines of this character, and in 100

accordance with my invention this movement is produced by the following described mechanism. The feed-dog 18 is connected to the feed-dog bar 19 which is pivotally supported from an extension on the bed-plate of the machine at 20^a by means of the links 20. The other end of the feed-dog bar is supported on an arm 21 which is fixed on a shaft 22 supported from the bed-plate in bearings 23 and 24. The shaft 22 is longitudinally reciprocated in its bearings which moves the arm 21 transversely back and forth under the end of the feed-dog bar 19 for raising and lowering the latter. The movement of the arm 21 under the end of the feed-dog bar raises and lowers the latter by the action of a ball 25 carried in recesses between them. In this construction, as clearly illustrated in Figs. 7 and 8, the feed-dog bar is provided with a recess 19^a which is deeper at one portion than another, and the end of the arm 21 is provided with a recess 21^a which is also deeper at one portion than another. These recesses are formed so that when their center lines are in vertical alignment, the deeper portion of one recess is opposite the shallower portion of the other. The ball 25, or any other suitable element, is carried between the end of the arm 21 and the feed-dog bar 19 in these recesses, and is retained in place by a spring 26 which draws the feed-dog bar 19 toward the end of the arm 21. When the arm 21 is shifted relative to the feed-dog bar 19 by the shaft 22 into a position in which the deeper portion of the recesses 19^a and 21^a are in vertical alignment, as shown in Fig. 7, the ball 25 is retained in the deeper portion of these recesses by the spring 26, and the feed-dog bar 19 occupies its lowermost position causing the feed-dog 18 to occupy its lowermost position out of engagement with the material under the presser-foot 13. On the other hand when the arm 21 is shifted by the shaft 22 relative to the feed-dog bar 19 from the position shown in Fig. 7 to that shown in Fig. 8 the shallower portions of the recesses 19^a and 21^a are brought into vertical alignment, the ball 25 is forced into these portions of the recesses, and raises the feed-dog bar 19 to its uppermost position which moves the feed-dog 18 into engagement with the material under the presser-foot 13 slightly raising the latter. The sides of the recesses 19^a and 21^a closely engage the ball 25 throughout the range of transverse movement of the arm 21 relative to the end of the feed-dog bar 19 so that any oscillation of the shaft 22 about its axis will be transmitted through the arm 21 and ball 25 to reciprocate the feed-dog bar without any movement of the arm 21 longitudinally relative to the feed-dog bar 19. In order to obtain the required sequence of movement of the feed-dog for feeding the material being sewn under the presser-foot, the shaft 22 is actuated in the following man-

ner. When the feed-dog is at the end of its range of movement toward the tip of the presser-foot, and the shaft 22 is at the extreme of its angular movement corresponding thereto, the latter is moved longitudinally toward the feed-dog bar 19 until the arm 21 is in the position relative to the feed-dog bar shown in Fig. 8. This movement of the arm 21 raises the feed-dog 18, by the feed-dog bar connected thereto, into engagement with the material under the presser-foot 13 and slightly raises the latter. The arm 21 is then turned, by rocking of the shaft 22 toward the needle bar 12, until the feed-dog is at the end of its stroke adjacent the presser-bar 13^a after which the arm 21 is moved transversely relative to the feed-dog bar 19 by moving the shaft 22 longitudinally away from the feed-dog bar to the position shown in Fig. 7, which lowers the feed-dog 18 out of engagement with the material being sewn. The arm 21 is then turned away from the needle bar 12 by rocking the shaft 22, which moves the feed-dog 18 in this lowered position to its initial position when it is again raised by movement of the arm 21 transversely relative to the feed-dog bar 19.

The necessary order of rocking and longitudinal movement of the shaft 22 for actuating the feed-dog 18, is obtained by the following described mechanism illustrated most clearly in Fig. 5 which is supported underneath the bed-plate 10 adjacent the shaft 22 and which is enclosed by the walls 10^a and a plate 10^b. A cam 27 is driven by a vertical shaft 28 and is arranged in a square opening 29^a provided in a bar 29. Rotation of the cam 27 in the square opening 29^a produces a movement of the bar 29 which is well-known in the art as a square or four-motion, consisting of the following successive movements, firstly movement transversely of the shaft 22, secondly movement longitudinally of the shaft 22, thirdly movement transversely of the shaft 22 toward the shaft 28, and then fourthly movement longitudinally of the shaft 22 to its initial position. A slot 30 is formed in the bar 29 for guiding it during its movement, under the action of the cam 27. The bar 29 is also guided by a collar 31 and rocker arm 32 which are fixed on the shaft 22 in contact with the bar 29 and disposed on opposite sides thereof. In addition to guiding the bar 29 the collar 31 and rocker arm 32 also transmit to the shaft any movement of the bar in either direction longitudinally of the shaft. The transverse movement of the bar 29 relative to the shaft 22 is transmitted to an oscillatory member 34 by a roller 35 carried by the bar and slidably fitting in a groove 36 in the oscillatory member which causes the latter to turn on its pivotal support 37. Turning of the oscillatory member rocks shaft 22 through a link 38 having a roller 39 on one end which is engaged by the

5 sides of a groove 40 extending the entire length of the oscillatory member and a shaft 41 connected to the link 38 and supported on rocker arms 32 and 33 which are secured to the shaft 22 in spaced relation to each other to permit adjustment of the link 38. In this construction a link 38 can be adjusted by means of guide pin 43, which extends into the groove 38^a in the link 38. The guide pin 10 43 also extends through a slot 42 which is parallel to the shaft 22 and is provided with a lock nut 43^a for retaining the link 38 in its position of adjustment corresponding to the length of the stitch to be formed by the 15 machine.

The length of the stitch formed can be adjusted by loosening the lock nut 43^a and shifting the link 38 on the shaft 41 relative to the oscillatory member 34. The length 20 of the stitch formed by the machine is decreased as the link 38 is brought nearer the pivotal support 37 because the movement of the oscillatory member 34 reciprocates the link 38 through a shorter range of movement 25 and correspondingly decreases the oscillation of the shaft 22 so that the range of reciprocation of the feed-dog 18 by the shaft 22 through the arm 21 and the feed-dog bar 19 will be correspondingly lessened. When the 30 link 38 is in its mid-position of adjustment the mechanism will not feed because the oscillation of the member 34 will not reciprocate the link 38. The position of the link 38 shown in Fig. 5 is for sewing forwardly, 35 that is, from the tip of the presser-foot 13 toward the presser-bar 13^a as shown in Fig. 5 or from the left to right of the machine as shown in Fig. 3. If it is desired to reverse the direction of sewing, the link 38 is shifted 40 relative to the member 34 to a position on the other side of its pivotal support 37 from that shown in Fig. 5 which changes the time 45 relation between the movement of the bar 29 and the feed-dog 18. In this position of adjustment when the bar 29 is in its extreme 50 position away from the shaft 28, the link 38, being on the same side of the pivotal support 37, will cause the shaft 22 to occupy a position at the opposite extreme of its oscillatory 55 movement to that which it would occupy if the link 38 were on the other side of the pivotal support 37 as shown in Fig. 5. As the range of reciprocatory movement of the feed-dog 60 is dependent upon the oscillation of the shaft 22, as above explained, the changing of the time relation between the movement of the bar 29 and the oscillation of the shaft 22 will also change the time relation between the movement of the feed-dog 18 and the movement 65 of the bar 29, and consequently the feed-dog will move in its raised position under the presser-foot in the opposite direction to that which it would move if the link 38 were in the position shown in Fig. 5 so that the direction 70 of feed is reversed. It will be noted that the

adjustment of the link 38 does not affect the longitudinal reciprocation of the shaft 22 so that the time relation of the longitudinal movement of the shaft 22 relative to the rotation of the shaft 28 and the cam 27 are not changed, so that the only effect of adjusting the position of the arm 38 is to vary the length 75 of the stitch formed by the machine or to reverse the direction of feed of the mechanism.

In operation of the sewing machine the electric motor 50 drives the loop-taker shaft 55 through the gears 52, 53, 56 and 57 which revolves the loop-taker 17 for pulling the thread from the needle around the bobbin cage in the usual manner. The needle bar 12 and the take-up 14 are actuated through shafts 59 and 28 which are driven at half the speed of the loop-taker shaft 55 by the connection through gears 55^a and 58. During the rotation of the loop-taker 17, and the operation of the needle bar 12 and the take-up 14 through the mechanisms above referred to, the material being sewn is fed under the presser-foot 13 in the following manner. The shaft 28 rotates the cam 27 in the square opening 29^a which forces the bar 29 transversely of the shaft 22 toward the shaft 28 to the extreme of its range of movement thereby rocking the shaft 22 through the oscillatory member 34, link 38, shaft 41 and rocker arms 32 and 33 so that the arm 21 on the end of the shaft 22 will be moved to the limit of its range of movement in a direction away from the tip of the presser-foot 13. As this movement takes place the arm 21 will be in a transverse relation to the feed-dog bar 19 shown in Fig. 7 so that the latter will be in its lowermost position and the feed-dog will be out of engagement with the material under the presser-foot. When the feed-dog 18 reaches the end of its range of movement the cam 27 will then force the shaft 22 longitudinally in its bearings toward the feed-dog bar 19 by its action on the bar 29 which is retained between the collar 31 and the rocker arm 32. This longitudinal movement of the shaft 22 will cause the arm 21 to move transversely of the feed-dog bar 19 and cause the ball 25 to raise the feed-dog bar 19 and bring the feed-dog 18 into engagement with the material which has been placed under the presser-foot 13. Turning of the cam 27 will then cause the bar 29 to move transversely of the shaft 22 away from the shaft 28 and rock the shaft 22 through the connection thereto including the oscillatory member 34, the link 38, shaft 41 and rocker arms 32 and 33. The rocking of the shaft 22 in this direction will cause the feed-dog 18 to move under the presser-foot 13 from its extreme position adjacent the tip of the presser-foot toward the other extreme of its range of movement adjacent the presser-bar 13^a which will feed the material under the needle in the usual manner. When the member 29 has reached the end of 105 110 115 120 125 130

its range of movement transversely of the shaft 22 away from the shaft 28 the feed-dog 18 will be at the end of its range of movement adjacent the presser-bar 13^a, and the cam 27 will then move the shaft 22 longitudinally away from the feed-dog bar and thereby lower the latter by bringing the arm 21 into a position relative to the feed-dog bar 19, shown in Fig. 7. Further turning of the cam 27 will cause the bar 29 to move transversely of the shaft 22 toward the shaft 28 which will move the feed-dog 18 in its lowered position to the other extreme of its movement by imparting a rocking motion to the shaft 22 through the oscillatory member 34, link 38, shaft 41, and rocker arms 32 and 33 which will move the feed-dog by its connection thereto through the arm 21, ball 25 and feed-dog bar 19. When the bar 29 has reached the end of its range of movement in this direction the cam 27 will move the shaft longitudinally toward the feed-dog bar 19 so that the arm 21 will be moved to a position relative to the feed-dog bar 19 shown in Fig. 8 and again raise the feed-dog 18 into engagement with the material under the presser-foot. This feeding operation will continue during the operation of the machine and is maintained in proper time relation with the action of the needle bar, the take-up, and the loop-taker through the mechanical connection to the common driving shaft 55 previously described. If it should then be desired to change the length of the stitch formed by the machine the lock-nut 43^a is loosened and the bar 38 thereby shifted along the shaft 41 to a position corresponding to the length of stitch required. If it is desired to reverse the direction of feeding of the machine so as to sew backward, as may be desired in some instances, for example in ornamental sewing, the bar 38 is shifted longitudinally of the oscillatory member 34 and the shaft 41 to a position on the opposite side 45 of the pivotal support 37 to that in which it is shown in Fig. 5, the length of stitch formed in sewing in the reverse direction being determined by the displacement of the link 38 away from the pivotal support 37 which is indicated by graduations 42^a adjacent the slot 42. The guide pin 43 can be readily shifted by means of the lock-nut 43^a so that the direction of sewing can be reversed without the necessity of removing the material being 50 sewn from the machine or if desired without stopping the machine.

Although I have shown my improved feeding mechanism in connection with a rotary lock-stitch sewing machine, it will be apparent that it may readily be applied to a sewing machine employing any other cooperating stitch forming mechanism than that herein disclosed. Many modifications of my improved feeding mechanism will occur to those skilled in the art, and I desire it to be under-

stood that my invention is not limited to the particular arrangement shown and described, and that I intend in the appended claims to cover all modifications which do not depart from the spirit and scope of my invention.

70

What I claim as new and desire to secure by Letters Patent of the United States, is:—

1. In a sewing machine feeding mechanism, the combination of a feed-dog, a shaft supported adjacent said feed-dog, means for oscillating said shaft about an axis extending longitudinally thereof and for longitudinally reciprocating said shaft, and means for reciprocating said feed-dog in response to the oscillation of said shaft and for raising and lowering said feed-dog in response to longitudinal reciprocation of said shaft.

75

2. In a sewing machine feeding mechanism, the combination of a feed-dog bar, a shaft supported adjacent said feed-dog bar, means for oscillating said shaft about an axis extending longitudinally thereof and for longitudinally reciprocating said shaft, means for supporting said bar at one end thereof, and means for supporting said bar at the other end thereof including means for reciprocating said feed-dog bar in response to the oscillation of said shaft and for raising and lowering said feed-dog bar in response to longitudinal reciprocation of said shaft.

80

3. In a sewing machine feeding mechanism, the combination of a feed-dog, a shaft supported adjacent said feed-dog, means for oscillating said shaft about an axis extending longitudinally thereof, means for reciprocating said shaft longitudinally thereof, means for reciprocating said feed-dog in response to the oscillation of said shaft and for raising and lowering said feed-dog in response to longitudinal reciprocation of said shaft, said last mentioned means including an arm fixed on said shaft extending adjacent said feed-dog, said arm having a recess therein deeper at one portion than another, means movable with said feed-dog having a like recess therein opening toward the recess in said arm, the deeper portion of said recess being opposite the shallower portion of the other when the center lines of said recesses are in alignment, and a member between said arm and the said means movable with said feed-dog extending into said recesses for transmitting movement from said arm to reciprocate and raise and lower said feed-dog.

100

4. In a sewing machine feeding mechanism, the combination of a feed-dog, a shaft supported adjacent said feed-dog, means for longitudinally reciprocating said shaft, an arm fixed on said shaft extending toward said feed-dog, said arm having a recess therein deeper at one portion than another, means movable with said feed-dog having a like recess therein opening toward the recess in said arm, the deeper portion of each said recesses being opposite the shallower portion of the

110

115

120

125

130

- other when the center lines of the recesses are in alignment, and a member carried in said recesses between said arm and said means movable with said feed-dog for transmitting movement thereto from the former to raise and lower the latter in response to longitudinal reciprocation of said shaft.
5. In a sewing machine feeding mechanism, the combination of a feed-dog, a shaft supported adjacent said feed-dog, means for oscillating said shaft about an axis extending longitudinally thereof, an arm fixed on said shaft extending toward said feed-dog, said arm having a recess therein, means movable with said feed-dog having a like recess therein opening toward the recess in said arm, and a member carried in said recesses for transmitting movement from said arm to said feed-dog for reciprocating the latter in response to oscillation of said shaft over a range of movement dependent upon the amplitude of the oscillatory movement of said shaft.
6. In a sewing machine feeding mechanism, the combination of a feed-dog, a shaft supported adjacent said feed-dog, a rotatable element supported adjacent said shaft, means for transmitting motion from said rotatable element to said shaft for oscillating the latter about an axis extending longitudinally thereof, means for varying the amplitude of the oscillatory movement of said shaft, means for longitudinally reciprocating said shaft, means for reciprocating said feed-dog over a range of movement dependent upon the amplitude of the oscillatory movement of said shaft, and means for raising and lowering said feed-dog in response to longitudinal reciprocation of said shaft.
7. In a sewing machine feeding mechanism, the combination of a feed-dog, a shaft supported adjacent said feed-dog, a rotatable element supported adjacent said shaft, means for transmitting motion from said rotatable element to said shaft for oscillating the same about an axis extending longitudinally thereof and for longitudinally reciprocating the same including means for varying the amplitude of the oscillatory movement of said shaft and the time relation between the motion of said movable element and the oscillatory movement of said shaft in order to provide for adjustment of the feed and reversal of the direction of feed of said mechanism, and means for reciprocating said feed-dog over a range of movement dependent upon the amplitude of the oscillatory movement of said shaft including means for raising and lowering said feed-dog in response to longitudinal reciprocation of said shaft.
8. In a sewing machine feeding mechanism, the combination of a feed-dog, a shaft supported adjacent said feed-dog, an oscillatory member supported adjacent said shaft, a pivotal support for said member having its axis extending transversely of said shaft, means for oscillating said member on said pivotal support, and means actuated by said member for oscillating said shaft about an axis extending longitudinally thereof.
9. In a reversible sewing machine feeding mechanism, the combination of a feed-dog, means including an oscillatory shaft for actuating said feed-dog, an oscillatory member arranged substantially parallel to said oscillatory shaft, means for supporting said member for oscillation about its mid-portion on an axis transverse to said oscillatory shaft, means including a vertical shaft for oscillating said member, and means actuated by said member for oscillating said oscillatory shaft, means for securing said last mentioned means at different distances on each side of the mid-portion of said member for providing adjustment of the amplitude of the oscillations of said shaft and of the time relation between the movement of said oscillatory member and the movement of said oscillatory shaft in order to vary the length of stitch formed by the machine in either direction of feed and to reverse the direction of feed of said mechanism.
10. In a sewing machine feeding mechanism, the combination of a feed-dog, means for actuating said feed-dog having an oscillatory and longitudinally reciprocatable shaft, an oscillatory member, means for supporting said member, means for oscillating said member and longitudinally reciprocating said shaft, and means actuated by said oscillatory member for oscillating said shaft about an axis extending longitudinally thereof.
11. In a sewing machine feeding mechanism, the combination of a feed-dog, means including an oscillatory and longitudinally reciprocatable shaft for actuating said feed-dog, an oscillatory member, means for supporting said member for oscillation about its mid-portion, means for oscillating said member about an axis extending transversely of said member, means for longitudinally reciprocating said shaft, and means actuated by said member for oscillating said shaft, said last mentioned means being adapted to engage said member at different distances on each side of its mid-portion for providing adjustment of the oscillatory movement of said shaft and of the time relation between the movement of said oscillatory member and the movement of said oscillatory shaft in order to vary the length of stitch formed by the machine in either direction of feed and to reverse the direction of feed of said mechanism.
12. In a reversible sewing machine feeding mechanism, the combination of a feed-dog, means including an oscillatory and longitudinally reciprocatable shaft for actuating said feed-dog, a bar extending transversely of said shaft, means on said shaft

preventing movement of said bar longitudinally relative thereto and for guiding said bar for movement transversely of said shaft, means engaging said bar for reciprocating the same transversely of said shaft and reciprocating said shaft longitudinally, an oscillatory member, means for pivotally supporting said member adjacent its mid-portion, said bar engaging said member for oscillating the latter, means for transmitting the oscillatory movement of said member to said shaft for oscillating the same, said last mentioned means being adapted to engage said member at a distance at either side of its mid-portion for providing adjustment of the oscillatory movement of said shaft and of the time relation between the movement of said oscillatory member and the movement of said oscillatory shaft in order to vary the length of stitch formed by the machine in either direction of feed and to reverse the direction of feed of the mechanism.

13. In a sewing machine stitch forming mechanism, the combination of a feed-dog, means including an oscillatory and longitudinally reciprocatable shaft for actuating said feed-dog, a bar extending transversely of said shaft, means on said shaft preventing movement of said bar longitudinally of said shaft and guiding the same for movement transversely thereof, means engaging said bar for reciprocating the same transversely of said shaft and reciprocating said shaft longitudinally, an oscillatory member, means for pivotally supporting said member adjacent its mid-portion, said bar engaging said member for oscillating the same, means for transmitting the oscillatory movement of said member to said shaft for oscillating the same, said last mentioned means being adapted to engage said member at a distance from said pivotal supporting means at either side thereof for providing adjustment of the oscillatory movement of said shaft and of the time relation between the movement of said oscillatory member and the movement of said oscillatory shaft in order to carry the length of stitch formed by the machine in either direction of feed and to reverse the direction of feed of the mechanism.

In witness whereof, I have hereunto set my hand this 6th day of June, 1927.

HUGH M. STEPHENSON.
